FURNACE BLOCK

Application filed March 7, 1928. Serial No. 259,722.

This invention relates to a block or tile that is especially useful for furnace walls that are provided with water cooling tubes. The block is made up of a metallic portion 5 that contacts with the tubes and a refractory portion that is held in a recess in the metal portion by means of cement.

The invention will be understood from the description in connection with the accompanying drawings in which Fig. 1 is a sectional elevation of one of the blocks; Fig. 2 is a section at right angles to that shown in Fig. 1; Fig. 3 is a section of a wall showing the blocks in place; and Fig. 4 is a side view of the wall. In the drawings reference character 1 indicates the metal or back portion of the block that may be made of cast iron, for example. The front or furnace side of the block is made of refractory material 2 that is cemented in place in a recess in the metal portion. The metal portion 1 is provided with a screw threaded hole 3 in the back thereof to accommodate a screw threaded bolt for keeping the block in place.

25 The metal or back portion 1 is provided with flanges 4 at the edges, thus leaving a seat or recess between the flanges. The flanges are made with their inner walls converging, thus making the outer edges of the 30 flanges thicker than the portion of the flanges that join the main body portion 1 of the metal block. There is thus provided a somewhat dovetail shaped seat or recess for the refractory portion of the block. The refractory 35 portion 2 of the block is provided with an extension 6 to extend into the recess between the flanges 4. The outer edges or walls 7 of the extension 6 are made to converge toward the front of the block, thus making these walls approximately parallel to the corresponding walls of the flanges 4. The width of the extension 6 is made slightly less than the distance between the flanges 4 so that spaces are left between the extension 40 and flanges. These spaces as well as a small

space between the faces of the metal and refractory portions of the block, are filled with cement 8 that may be made of clay and water glass, for example, thus retaining the refractory portion 2 in place on the metal portion 1 when the cement hardens. 50

In the view shown in Fig. 2, the distance across the widest portion of the extension 6 is made slightly greater than the shortest distance between the flanges 4 so that one edge 55 of the refractory portion 2 is inserted and pushed all the way over to one side, whereupon the other edge can be inserted and the refractory portion centered or adjusted, to equalize the spaces on opposite sides and cement 8 keeps the refractory portion in place. 60

Figs. 3 and 4 illustrate the manner in which the blocks may be installed. Reference character 10 indicates a row of water wall 65 tubes that are spaced apart and saddles or holding members 11 extend from one tube to the next on the side opposite the furnace. These saddles or supports 11 have rounded portions 12 that fit the outside of the tubes 70 and screw bolts 13 that are provided with nuts 14 extend through the saddles or supports 11 into the holes 3 in the blocks so that when the nuts 14 are tightened the metal portions of the blocks will be securely clamped 75 against the tubes. The metal portions of the blocks are provided with rounded portions 15 to fit the tubes. 80

It has been found that decided advantages are obtained by cementing the refractory portions to the metal portions instead of casting the metal portion in place as has heretofore been done. The heat conductivity of the cement being small, a higher temperature is obtained on the furnace side of the refractory 85 material than would be the case if the metal portions were cast in place on the refractory. This is desirable because high temperatures are required on the furnace side for best combustion efficiency. Beside, it has been found 90

that the refractory material is less liable to spall when cemented to the metal than it is when the metal is cast in place on the refractory. There are no initial casting strains 5 on the refractory when the same is cemented in place as above described.

The invention is also useful, for example, when the refractory material is made of carbborundum. In that case, a cement of high 10 heat conductivity composed largely of carbborundum, for example, can be used and the danger of the refractory material spalling is decreased. Changes and modifications can be made without departing from the spirit 15 or scope of the invention.

I claim:

1. A furnace wall comprising blocks, each having a metallic backing, refractory facings supported on said backings forming the face 20 of a combustion chamber and covering said backings and shielding same from the heat of said furnace, a layer of relatively low heat conductive material located between each backing and refractory facing whereby the 25 rate of heat transfer between said backings and refractory facings is reduced so as to permit a high surface temperature on the side of said facings toward the furnace and relatively low temperature of the metal of 30 said backing.

2. In a furnace chamber, a wall comprising a block adapted to form a part of the wall of said furnace chamber, a metallic supporting member having a recess formed therein 35 on the side facing said furnace chamber, a refractory block having a portion located within said recess and supported by said metallic member, said block covering the entire face of said member on the furnace chamber side to shield said member from the radiant heat of said furnace, and a layer of 40 relatively poor heat conductive material located between said block and said member.

3. A furnace wall comprising blocks, each having a metallic backing, refractory facings supported on said backings forming the face of a combustion chamber and covering said backings and shielding same from the heat of said furnace, a layer of material whose 45 heat conductivity is low relative to said backing located between each backing and refractory facing whereby the rate of heat transfer between said backings and refractory facings is reduced so as to permit a high surface temperature on the side of said facings toward the furnace and relatively low temperature of the metal of said backing.

4. A furnace wall comprising blocks, each 50 having a metallic backing, refractory facings supported on said backings forming the face of a combustion chamber and covering said backings and shielding same from the heat of said furnace, a layer of material 55 whose heat conductivity is low relative to

said backing located between each backing and refractory facing whereby the rate of heat transfer between said backings and refractory facings is reduced so as to permit a high surface temperature on the side of said facings toward the furnace and relatively low temperature of the metal of said backing, and water tubes along said furnace wall to which said blocks are connected with the refractory facings of said block facing the inside of said furnace.
